The ornamental design for an adaptor for power tools, as shown and described.

DESCRIPTION

FIG. 1 is a front elevational view of a first embodiment of an adaptor for power tools of the design;

FIG. 2 is a rear elevational view thereof;

FIG. 3 is a top plan view thereof;

FIG. 4 is a left side elevational view thereof;

FIG. 5 is a first perspective view thereof; and

FIG. 6 is a second perspective view thereof;

FIG. 7 is a front elevational view of a second embodiment of an adaptor for power tools of the design;

FIG. 8 is a rear elevational view thereof;

FIG. 9 is a top plan view thereof;

FIG. 10 is a left side elevational view thereof;

FIG. 11 is a first perspective view thereof; and

FIG. 12 is a second perspective view thereof;

FIG. 13 is a front elevational view of a third embodiment of an adaptor for power tools of the design;

FIG. 14 is a rear elevational view thereof;

FIG. 15 is a top plan view thereof;

FIG. 16 is a left side elevational view thereof;

FIG. 17 is a first perspective view thereof; and

FIG. 18 is a second perspective view thereof;

FIG. 19 is a front elevational view of a fourth embodiment of an adaptor for power tools of the design;

FIG. 20 is a rear elevational view thereof;

FIG. 21 is a top plan view thereof

FIG. 22 is a left side elevational view thereof;

FIG. 23 is a first perspective view thereof; and

FIG. 24 is a second perspective view thereof;

FIG. 25 is a front elevational view of a fifth embodiment of an adaptor for power tools of the design;

FIG. 26 is a rear elevational view thereof;

FIG. 27 is a top plan view thereof;

FIG. 28 is a left side elevational view thereof;

FIG. 29 is a first perspective view thereof; and

FIG. 30 is a second perspective view thereof;

FIG. 31 is a front elevational view of a sixth embodiment of an adaptor for power tools of the design;

FIG. 32 is a rear elevational view thereof;

FIG. 33 is a top plan view thereof;

FIG. 34 is a left side elevational view thereof;

FIG. 35 is a first perspective view thereof; and

FIG. 36 is a second perspective view thereof;

FIG. 37 is a front elevational view of a seventh embodiment of an adaptor for power tools of the design;

FIG. 38 is a rear elevational view thereof;

FIG. 39 is a top plan view thereof;

FIG. 40 is a left side elevational view thereof;

FIG. 41 is a first perspective view thereof; and,

FIG. 42 is a second perspective view thereof.

The broken lines immediately adjacent to the shaded and solid line areas represent the boundaries of the claimed design while all other broken lines are directed to unclaimed environment. All broken lines shown in the views represent the portions of the design that form no part of the claim.
